TELESCOPIC SIGHT MOUNT FOR RIFLES

Charles M. O'Neil, Hopkins, Minn., assignor of
one-half to Donald S. Hopkins, Spokane,
Wash.

Application March 27, 1939, Serial No. 264,388

4 Claims. (Cl. 33—50)

My invention relates to firearms and particularly to protectors for telescopic sights of rifles.

A telescopic sight of a rifle is in a relatively exposed position thereon and is somewhat delicate in regard to maintenance of a properly adjusted position of the sight relative to the bore of the rifle. Consequently rifles equipped with telescopic sights must ordinarily be carefully handled and protected to prevent loss of adjustment of the sight and damage thereto. The need for protection and careful handling would usually preclude the use of rifles having telescopic sights in military service or for any other use wherein rough handling is difficult to avoid.

An object of my invention is to provide a device for effectively protecting the telescopic sight of a rifle against loss of adjustment or damage from contact with other objects and from jarring of the telescopic sight.

Another object is to provide such a protection device affording access to the adjustment elements of a telescopic sight and including protection means therefor.

Still another object is to provide such a device supported from a firearm independently of a telescopic sight.

Yet another object is to provide such a device permitting yielding of a telescope sight responsive to jarring thereof within limits wherein the sight cannot become permanently deflected but will return to its normal position due to its own resiliency.

A further object is to provide such a device of light, compact, simple, rugged and inexpensive construction.

These and other objects and advantages of the invention will more fully appear from the following description made in connection with the accompanying drawing, wherein like reference characters refer to the same or similar parts throughout the views, and, in which:

Fig. 1 is a side view of a telescopic sight equipped military rifle having an embodiment of my invention particularly suited therefor mounted thereon;

Fig. 2 is a partial top view;

Fig. 3 is a sectional view taken on the line 3—3 of Fig. 2 as indicated by the arrows;

Fig. 4 is a sectional view taken on the line 4—4 of Fig. 2 as indicated by the arrows;

Fig. 5 is a sectional view taken on the line 5—5 of Fig. 2 as indicated by the arrows;

Fig. 6 is a sectional view taken on the line 6—6 of Fig. 2 as indicated by the arrows;

Fig. 7 is a partial top view of a telescopic sight equipped sportsman's rifle having an embodiment of my invention particularly suited therefor mounted thereon;

Fig. 8 is a partial side view;

Fig. 9 is a sectional view taken on the line 9—9 of Fig. 8 as indicated by the arrows;

Fig. 10 is a sectional view taken on the line 10—10 of Fig. 8 as indicated by the arrows; and

Fig. 11 is a sectional view taken on the line 11—11 of Fig. 8 as indicated by the arrows.

Referring to the drawing and particularly to Figs. 1 to 6 inclusive, a firearm 12 is shown having thereon a telescope sight unit 13 and an embodiment of my invention particularly suited to firearms for military use or other relatively rough service. The telescope sight unit is of conventional construction and includes outwardly projecting adjustment elements 14 and 15.

As shown in Fig. 4, the telescope sight unit 13 is rigidly attached in its medial portion to the rifle 12 by means of a narrow clamping element 19 secured to the rifle 12 by suitable means such as the screws 20. By reference to the drawing, it will be noted that clamping element 19 engages only a very narrow zone of the external medial portion of the sight, thereby providing for slight deflection of the sight through resiliency of element 19 and the inherent resiliency of the sight casing itself.

At the forward end of the telescope sight unit I provide a guard element 18, as shown in Fig. 3, having a general figure eight shape. The lower portion of the guard element 18 closely encircles and is fixed to the barrel 12a of the rifle 12. The upper portion of the guard element 18 encircles the forward portion of the telescope sight unit 13 in slightly radially spaced relation thereto so as to permit deflection of the telescope sight unit responsive to jarring thereof through a distance so limited that the telescope sight unit will return to its normal position due to its own resiliency.

I provide a casing 16 to be mounted on the firearm 12 and to contain the telescope sight unit 13 so that the telescope sight unit will not come in contact with objects so as to become damaged or be jarred out of adjustment. While the shield 16 may take various forms the illustrated form is constructed to have a general inverted U-shaped cross section so that the shield 16 may be disposed parallel to the telescope sight unit 13 in straddling relation therewith. The shield 16 may be made of sheet material such as sheet metal of suitable thickness.

Means is provided for attaching the shield 16 to the firearm 12. At the forward end of the shield 16 apertured ears 17 are formed thereon and may be attached to the guard element 18 by means of screws 17a screw threadedly engaged in suitably located internally screw threaded apertured portions of the guard element 18 as shown in Fig. 3.

The medial portion of the shield 16 is notched to obtain clearance between the shield 16 and the clamping element 19 and screws 20.

The rear portion of the shield 16 is slightly radially spaced from the rear portion of the telescope sight unit 13 and is provided with apertured ears 21 which may be attached to suitably located internally screw threaded apertured portions of the firearm 12 by means of screws 22.

Means is provided for protecting the outwardly projecting adjustment elements 14 and 15 of the telescope sight without preventing access to the adjustment elements for the purpose of adjustively manipulating the same. For this purpose I provide partial enclosures for the adjustment elements 14 and 15, these enclosures having open sides permitting access to diametrically opposite portions of the peripheries of the adjustment elements 14 and 15. While these enclosures may take various forms I prefer to form them of strap-like strips 23 and 24 of sheet metal. As shown in Figs. 1, 2, and 5 the protective elements 23 and 24 extend parallel to the length of the firearm 12 and arch over the respective adjustment elements 14 and 15. The guard element 16 is, of course, provided with apertures therethrough to accommodate the adjustment elements 14 and 15 so that these adjustment elements may project through and outwardly of the shield 16. The protective elements 23 and 24 are of general U-shaped construction with the medial portions extending diametrically over the respective adjustment elements 14 and 15 and the free ends secured to the shield 16 integrally or otherwise as desired.

Where my shield 16 is used with a telescope sight wherein the adjustment elements are near the forward end thereof protective elements 25 and 26 shown in Figs. 1, 2, and 6 are provided on the forward portion of the shield 16, and the shield 16 is also suitably apertured at the locations of the protective elements 25 and 26 to accommodate adjustment elements similar to the elements 14 and 15 but located on the forward portion of the telescope sight unit.

Figs. 7 to 11 illustrate a form of telescope sight protective device adapted for use in firearms for sporting purposes or other purposes wherein the service is not as rough as in military use or similar uses. This form of my protective device is shown associated with a firearm 27 and a telescope sight unit 28. The telescope sight unit 28 is attached to the firearm 27 in its medial portion by a bracket 30. As shown in Fig. 10, the bracket 30 is of general figure 8 shape with the lower portion encircling the barrel 27a of the rifle 27 and the upper portion encircling the telescope sight unit 28. The lower portion of the bracket 30 is fixed on the rifle barrel 27a by any suitable means. The upper portion of the bracket 30 is split, as shown, and is held together by means such as the screws 30a so as to enable clamping of the telescope sight unit 28 therein.

My guard unit for the forward end of the

telescope sight 28 is shown in Fig. 9 and consists of an element 29 of figure 8 shape with its lower portion closely encircling and fixed to the rifle barrel 27a and its upper portion encircling the forward end of the telescope sight unit 28 in slightly radially spaced relation thereto.

My guard unit for the rear portion of the telescope sight 28 is shown in Fig. 11 and includes a tubular element 31 encircling the rear end of the telescope sight 28 in slightly radially spaced relation therewith. The tubular element 31 is provided with apertured longitudinally extending flanges 32 which may be secured to the frame of the rifle 27 by suitable means such as the screws 33.

The guard element 31 is provided with a forwardly projecting extension 33 of U-shaped cross section and disposed in straddling, radially spaced relation with the rear portion of the telescope sight unit 28. The illustrated type of telescope sight unit is, as indicated in Fig. 8, provided with outwardly projecting adjustment elements 28a and 28b and the U-shaped extension or shield 33 is suitably apertured to accommodate projection of the adjustment elements 28a and 28b through the shield element 33 and therebeyond.

Protective means is provided for the adjustment elements 28a and 28b. This protective means consists of elements 34 and 35 similar to the elements 23 and 24 of the previously described embodiment of my invention and mounted on the shield element 33 in a manner similar to that in which the protective elements 23 and 24 are mounted on the shield 16 of the previously described form.

It should be readily seen that my protective shields 16 and 33 will protect a telescope sight against contact with objects which would otherwise result in damage to or misadjustment of the telescope sight and that the protective elements 23, 24, 25, 26, 34, and 35 are capable of protecting the adjustment elements of a telescope sight and yet afford access to the adjustment elements for the purpose of adjustive manipulation thereof. It should also be seen that the guard units 16, 18, 29 and 31 will permit a slight deflection of a telescope sight but so limit such deflection that the telescope sight will return to its normal position due to its own resiliency.

It is apparent that I have invented a novel, effective, light, compact, rugged, and inexpensive form of telescope sight protective equipment which is readily adapted for incorporation thereon in the structure of a firearm.

It will, of course, be understood that various changes may be made in the form, details, arrangement and proportions of the various parts without departing from the scope of my invention.

What is claimed is:

1. In combination with a fire arm and a telescope sight therefor, a protective device for said sight comprising, an element rigidly carried by said fire arm and clamping a relatively narrow zone on the external medial portion of said sight, a guard element adjacent one of the ends of said sight rigidly secured to said fire arm and having an annular inner periphery normally spaced a slight distance outwardly of the outer periphery of said sight and encircling the same concentrically to limit deflection of said sight from the normal position thereof while permitting slight deflection through the striking of said sight against an object, the resiliency of

50

2,266,331

3

said sight and said clamping element returning said sight to normal position when so struck.

2. In combination with a fire arm and a telescope sight therefor, a protective device for said sight comprising, an element rigidly carried by said fire arm and clamping a relatively narrow zone on the external medial portion of said sight, a guard element for the forward portion of said sight rigidly secured to said fire arm and having a circularly curved inner periphery spaced a slight distance outwardly of the outer periphery of said sight and concentrically encircling the same, and a protective shield covering at least the rear portion of said sight and rigidly secured to said fire arm, said shield also having a circularly curved inner periphery normally spaced a slight distance outwardly of the outer periphery of the rear of said sight and concentrically encircling the same, said guard element and shield limiting deflection of said sight from the normal position thereof, while permitting slight deflection through the striking of said sight against an object.

3. In combination with a fire arm and a telescope sight therefor, a protective device for said sight comprising, an element rigidly carried by

5 said fire arm and clamping a relatively narrow zone on the external medial portion of said sight, a protective shield comprising a trough-shaped member of substantially inverted U-shaped cross section encircling at least the rear portion of said sight, means for securing said shield to said fire arm, the upper portion of the inner periphery of said shield being normally concentric with the encircled portion of said sight but spaced a slight distance therefrom to limit deflection of said sight from the normal position, while permitting slight deflection through the striking of said sight against an object, the resiliency of said sight and said clamping element returning said sight to normal position when so struck.

10 15 20 25 4. The structure set forth in claim 3, and said shield extending substantially the length of said sight and covering the same, an outwardly projecting adjustment element on said sight, said shield having an aperture for projection of said adjustment element therethrough, and a protective strip bent into U-shape outwardly of said adjustment element and over said aperture and secured to said shield.

CHARLES M. O'NEIL.
